UNITED STATES PATENT OFFICE.

ALBERT WANNER, JR., OF NEW YORK, N. Y.

FURNITURE-BRACE.

1,124,080.

Specification of Letters Patent.

Patented Jan. 5, 1915.

Application filed June 26, 1914. Serial No. 847,425.

To all whom it may concern:

Be it known that I, ALBERT WANNER, Jr., a citizen of the United States, residing at New York city, in the county of New York and State of New York, have invented certain new and useful Improvements in Furniture-Braces, of which the following is a specification.

This invention relates to means for bracing joints in furniture and other structures and it consists in a novel brace so constructed as to require but the minimum of cost to manufacture and to impart unusual strength to the joint to which it is applied.

15 I have illustrated my invention in the accompanying drawing in its adaptation to the joint between the seat-ring or frame and one of the back legs of a chair of the bent-wood type, such joint representing a type 20 wherein, without bracing means, in service the maintaining of the parts in permanent or rigid relation to each other is substantially impossible to attain.

In said drawing, Figure 1 is a perspective view of the seat-ring and back-leg joint of a chair of the bent-wood type, with the improved brace in position thereon; Fig. 2 is a front elevation of the brace; Fig. 3 a rear elevation thereof; and, Fig. 4 a vertical sectional view of said brace.

a designates the ring forming the frame of the seat of a chair of the bentwood type, and *b* is one of the back legs of such chair.

The improved brace includes the upper 35 and upwardly projecting member *c*, the lower and downwardly projecting member *d*, said members being arranged substantially parallel with each other, the intermediate member *e* which is arranged at an incline and connects members *c* and *d*, and the angular wings *f*, one at each side of the intermediate member *e*.

Member *c* is formed on the side thereof adjacent to the plane in which lies the member *d* with a bearing bead or flange *c'* along so much of its margin or edge as is free, whereby to strengthen said member; said member is formed with a vertical slot *c''*.

Member *e* is concavo-convex, by preference, its relatively under side having the convexity, whereby to impart strength to the bracket and improve its appearance.

Member *d* is part-cylindrical in elevation, its concave side corresponding to the flanged or beaded side of member *c*, so that it is

equally adapted to flat, angular or cylindrical surfaces. It has a hole *d'*.

The wings *f* are right angular in form, the upper edge of each being horizontal and the rearward edge vertical and merging into the corresponding edge of member *d*.

The bracket, as thus described, is preferably stamped out of one piece of sheet metal, whereby to cheapen the bracket and give it lightness, with strength.

65 The bracket is assembled with the ring *a* and leg *b* of the chair in the manner shown in Fig. 1, where *g* is a lag screw passed through the slot *c'* of member *c* and into the ring and leg, so that these three parts 70 are securely bound together, *h* being a washer between the head of the lag screw and member *c* of the bracket, and *i* is an ordinary wood screw introduced through hole *d'* of member *d* and driven into the leg 75 *c*. In assembling the bracket with the leg and ring the wings *f* are fitted well into the angle formed between the surface of the leg and the under surface of the ring, so that the ring bears downwardly on and is 80 thus supported by said wings.

It will be understood that the object of the slot *c''* is to permit the lag screw to be passed through member *c* at any such elevation as conditions may require.

85 Having thus fully described my invention, what I claim as new and desire to secure by Letters Patent is:—

1. A brace for joints of the class described including an upper and a lower 90 member in substantially parallel vertical planes and each having an opening for a securing device, and an inclined concavo-convex intermediate member, said members being integral.

95 2. A brace for joints of the class described including an upper and a lower member in substantially parallel vertical plane and each having an opening for a securing device, and an inclined concavo-convex intermediate member, said members being integral, the underneath side of the intermediate member being its convex side.

3. A brace for joints of the class described including an upper and a lower 105 member arranged in substantially vertical planes and each having an opening for a securing device, the upper member having a marginal bearing flange on the side thereof facing the plane of the lower member 110

and the lower member being part-cylindrical in plan, and an inclined concavo-convex intermediate member, said members being integral.

4. A brace for joints of the class described including an upper member, a lower member having its upper end below the lower end of the upper member, said members being in substantially parallel vertical planes, and each having an opening for a securing device, an intermediate member joining the first two members, and upstanding lateral angular wings on the intermediate member, said members and the wings being integral.

5. A brace for joints of the class described including an upper member, a lower

member having its upper end below the lower end of the upper member, said members being in substantially parallel vertical planes and each having an opening for a securing device, an intermediate member joining the first two members, and upstanding lateral angular wings on the intermediate member, said members and the wings being stamped from a single piece of sheet metal.

In testimony whereof I affix my signature in presence of two witnesses.

ALBERT WANNER, JR.
